EXAMPLE 2

When the following olefins are reacted with

and the process described in Example 1 is carried out, the products as shown in the following table are obtained.

Olefin	Product
$\text{CH}_2=\text{CH}(\text{CH}_2)_{17}\text{CH}_3$	$\text{CH}_3(\text{CH}_2)_{10}\text{SiOCH}(\text{CH}_3)_2$
$\text{CH}_2=\text{CH}(\text{CH}_2)_9\text{CH}_3$	$\text{CH}_3(\text{CH}_2)_{11}\text{SiOCH}(\text{CH}_3)_2$
$\text{CH}_2=\text{CH}(\text{CH}_2)_7\text{CH}(\text{CH}_3)_2$	$\text{CH}_3(\text{CH}_2)_7\text{CH}(\text{CH}_2)_9\text{SiOCH}(\text{CH}_3)_2$
$\text{CH}_2=\text{CH}(\text{CH}_2)_{14}\text{CH}_3$	$\text{CH}_3(\text{CH}_2)_{14}\text{SiOCH}(\text{CH}_3)_2$

15 That which is claimed is:

1. An alkyldiphenylisopropoxysilane having a formula

wherein n is an integer of from 12 to 45.2. The alkyldiphenylisopropoxysilane according to claim 1 wherein n is 18.
